APPARATUS FOR APPLYING GETTERS TO
LAMP FILAMENT SUPPORTSPaul Vargo, Lyndhurst, and Thomas A. Foster,
Jr., Cleveland, Ohio, assignors to General Elec-
tric Company, a corporation of New York

Application February 28, 1952, Serial No. 273,936

7 Claims. (Cl. 118—221)

1

Our invention relates to apparatus for manufacturing electric incandescent lamps and other electrical devices and, more particularly to apparatus for automatically applying a chemical clean-up agent or "getter" in the form of a paste to the parts of the filament mount of incandescent lamps and other electrical devices. The clean-up agents, or getters, react under the heat of operation of the electrical device to absorb or transform into non-injurious materials those contaminating materials which remain in said devices after they have been exhausted and sealed.

One object of our invention is to provide apparatus for automatically applying a measured amount of a getter in paste form to specific portions of the leading-in wires of a filament mount of an electric device. The apparatus is adaptable to operation at one work station of an automatic machine for making the filament mounts, and is capable of operation without attention for relatively extended periods.

Another object of our invention is to provide improved apparatus which will obviate the deficiencies of prior gettering apparatus by effecting the transfer of getter by means of a notched metal finger and by causing said metal finger to pass along a definite portion of the leading-in wire. Apparatus heretofore employed provided for the getter to be carried to the mount by means of a brush which required frequent cleaning in order to retain its operating efficiency. The brush lost resiliency and form very shortly after being placed in operation because of the quick drying properties of the getter and was soon covered by a dry residue. The proper dosage, thickness of getter coating or position of the coating could not be maintained under these conditions.

Further advantages of apparatus comprising our invention is that it provides a convenient means of applying getter to more than one leading-in wire of a mount at the same time, and it is suited to the application of getter to different portions of the leading-in wires at the same time. The apparatus also avoids the application of heavy concentrations or blobs of the getter which may not operate effectively, and it further avoids the spilling over of getter onto the ends of the filament which is very likely to be injurious thereto.

Still other features and advantages of our invention will appear from the following description of a species thereof and from the drawing.

In the drawing, Fig. 1 is a perspective view of gettering apparatus comprising our invention in the course of applying getter to a plurality of leading-in wires extending to the two filaments of a mount; Fig. 2 is a perspective view of a getter-applying arm of said apparatus on a larger

2

scale and showing the opposite side of said arm from that appearing in Fig. 1; Fig. 3 is a perspective view of the operating means of the gettering apparatus on a smaller scale than Fig. 1; and Fig. 4 is an end view of the applicator arm with the fingers thereof at the getter receiving position and indicated in dot-dash lines at the delivery position.

The gettering apparatus disclosed in the drawing is preferably located at operative relation to means for presenting the filament mount of a lamp thereto at regular intervals. As shown, the apparatus is located at operative relation to the jaws 1—2 and the locating plate 3 of a head 15 of a carrier advancing the mount 4 laterally to and beyond the position shown. The gettering apparatus is mounted at a fixed position on a table 5 located below and surrounding the carrier which may be, for instance, of the type included in the automatic mount making machine disclosed in Illingworth Patent 1,733,881 dated October 29, 1929. Also included in the combination is a drive shaft 6 located below the table 5 and turning through one revolution while each mount 4 remains before the gettering apparatus, as is also the usual manner of operating mount-making apparatus.

Each cycle of operation of the gettering apparatus effects the transfer of a quantity of getter to the mount 4 by the swinging movements of an arm 7 which carry it horizontally back and forth between a spoon 8, containing a small quantity of the semi-fluid getter 9 contained within the reservoir 10, and the mount 4. The swinging movement of the arm 7, which is comprised of the hub portion 11 and the extending rod portion 12, results from a corresponding rotation of the vertical shaft 13 holding said hub portion 11 and is brought about by operating means located below the table 5 and engaging the end of the shaft 13 extending beyond the base 14. The back, or getter pick-up swing, of the arm 7, which initiates the cycle of operation, is the result of rotation of a high portion of the cam 15 of the operating means into engagement with the roller 16 on the bell crank 17 and the resulting rocking or turning movement of said bell crank 17 about the pivot screw 18 in a bracket 19 depending from the lower surface of the table 5. A connecting rod 20 transfers the motion of the bell crank 17, which occurs against the tension of the return spring 17', to the arm 21 clamped to said shaft 13. The forward, or getter-delivery swing, of the arm 7 follows the reception of getter by the metal fingers 22 and 23 on the cap 24 at the end of the rod portion 12 of the arm 7.

The getter carrying fingers 22 and 23, as shown particularly in Fig. 4, extend from essentially radial slots in the cap 24 and, at the time of

their engagement with the mount are positioned somewhat below (about 30 degrees) the horizontal. The back swing of the arm 7, however, causes the fingers 22 and 23 to be rotated about the axis of said arm 7 to a downwardly inclined position where their ends are able to dip into the getter pool in the spoon 8. This rotation is effected when the tab 25 on the rod portion 12 strikes the stationary cam 26 so that it is pushed to a trailing position with respect thereto. The tab 25 is fixed on the rod portion 12 and, in moving as described, turns said rod portion 12 in the hub portion 11 against the twisting resistance of a torsion spring 27 located thereabout and with respective ends attached to the tab 25 and within an opening in the cap nut 28. The externally threaded cap nut 28 is screwed tightly into the hub portion 11 at a position to hold the enlarged end of the rod portion 12 therein by shouldered engagement therewith and does not rotate with respect to the hub portion 11. During the back swing of the arm 7, the tab 25 slides along the bottom surface of the arcuate cam 26, which is supported by the standard 29, and the fingers 22 and 23 are at a position (Fig. 4) below and on the opposite side of a vertical plane through the axis of the arm 7 which causes the ends thereof to be at the same elevation and which therefore allows them to be wet equally by a pool of getter.

The getter is applied to the ends of the fingers 22 and 23 by a vertical movement of spoon 8 which carries said spoon 8 from within the main supply of getter in the reservoir 19 to a raised position where said ends are immersed in the getter pool therein. This manner of supplying the getter fingers 22 and 23 assures application thereto of getter of a uniform consistency, and is brought about by the corresponding movements of the vertical rod 30 to which said spoon 8 is attached by means of an inverted U-shaped strap 31 and the clamp block 32. The operating means, located below the table 5 and the support standard 33 for the rod 30, provides for the vertical motion of said rod 30 by oscillation of the operating lever 34 about a pin in the stationary bracket 35 in accordance with the advance of differently shaped portions of the cam 36 on shaft 6 into engagement with the roller 37. A helical spring 38 extending between the end of the operating lever 34 and a part of table 5 (not shown) causes said lever 34 to follow the contour of the cam 36. As shown, the form of the cam 36 is such that the spoon 8 is out of the reservoir 19 only for the moment required to allow the getter to wet the fingers 22 and 23, and is immediately plunged back into the reservoir 19. This manner of operation retards the drying and consequent thickening of the getter as much as possible and constantly stirs and agitates the full getter supply so that a very uniform mixture thereof is always available. Further agitation of the getter supply is provided by a steady stream of air bubbles passed upward therethrough from a pipe 39 extending to a point near the bottom of the reservoir 19 and connected to an air supply through flexible hose 40.

The return swing of the arm 7 which moves the getter fingers 22 and 23 to operative relation to the mount 4 causes the tab 25 to slide back along the cam 26 without causing said fingers 22 and 23 to change their relation in said arm 7. At the termination of the swing, however, the tab 25 passes beyond the end of the cam

26 and said fingers 22 and 23 are turned back to the position shown in Figs. 1 and 2 by the uncoiling of the spring 27. The rotation of the rod portion 12 of the arm 7 turns the fingers 22 and 23 90 degrees around the axis of said arm 7 to the position where they are located at substantially thirty degrees to the horizontal and where their ends are in the vertical plane of the leads 43 and 44. At the completion of the movement, the radially extending pin 41 in the rod portion 12 bears against the stop pin 42 in the cap nut 28. Because the fingers 22 and 23 are of different length and are offset circumferentially around the arm 7, the ends of said fingers 22 and 23 take different positions along said leads 43 and 44 which positions are at uniform distances from the filaments 45 and 46 held by said leads 43 and 44. In the usual manner of operating the apparatus the ends of the fingers 22 and 23 partially encompass but do not contact the leads 43 and 44; however, a variation in the position thereof may cause one or both of said leads 43 and 44 to be contacted by said fingers 22 and 23 but otherwise not to be harmed since the angular position of said fingers 22 and 23 and the slight pressure of the spring 27 permits them to swing back. The ends of the fingers 22 and 23 lie in a vertical plane corresponding to the plane of the leads 43 and 44 at the time the getter is applied and accordingly will dip to equal depth into the getter pool in the spoon 8 if the rod portion 12 of the arm 7 is turned back ninety degrees, as is the degree of movement thereof in this particular instance. Notches in the ends of the fingers 22 and 23 permit them to carry a sufficient supply of getter and also permit the fingers 22 and 23 to extend part way around the leads 43 and 44.

Completion of the gettering operation is effected by a short upward movement of the arm 7 which carries the getter fingers 22 and 23 up along the leads 43 and 44. This motion of the fingers 22 and 23 spreads the getter more thinly over the leads 43 and 44 and avoids the formation of blobs and heavy concentrations thereof heretofore obtained with other types of apparatus. The upward wiping action of the arm 7 results when the shaft 13 is moved correspondingly by the operating means and in particular by the operating lever 47 under the influence of cam 48 and roller 49. The operating lever 47 turns about the fixed shaft 50 and forces the shaft 13 upward against the compression resistance of the helical spring 51 located about the portion of the shaft 13 between the arm 7 and the table 5. The return downward movement of the arm 7 does not occur until the arm 7 is backed away from the mount 4 and another mount 4 is indexed into place by the carrier.

Although a preferred embodiment of our invention has been disclosed, it will be understood that the invention is not to be limited to the specific construction and arrangement of parts shown, but that they may be widely modified within the spirit and scope of our invention as defined in the appended claims.

What we claim as new and desire to secure by Letters Patent of the United States is:

1. Apparatus for applying a getter paste to a lead wire of a mount comprising means for holding the mount at a work station, means for supplying a pool of the getter paste at a position adjacent said work station, an arm having an axially rotatable end portion and movable be-

tween the getter supplying means and the work station, a finger having a notched end extending laterally from the rotatable end portion of the arm, and means for rotating the rotatable end portion of the arm during the said movement thereof to cause the notched end of the finger to be immersed in the getter pool at one terminus of its motion and to cause the notched end to take a position about a portion of the said lead wire at the other terminus of said motion.

2. Apparatus for applying a getter paste to a lead wire of a mount comprising means for holding the mount with a lead wire thereof extending vertically at a work station, means for supplying a pool of getter paste at a position adjacent said work station, an arm having an axially rotatable end portion and movable through a horizontal plane between the getter supplying means and the work station, a finger having a notched end extending laterally from the rotatable end of the arm, and means for turning the rotatable end portion of the arm during the movement thereof to cause the notched end of the finger to extend downward from said arm and be immersed in the getter pool at one terminus of the motion thereof and to cause said notched end to extend approximately horizontally and take a position about a portion of the said lead wire at the other terminus of said motion.

3. Apparatus for applying a getter paste to a lead wire of a mount comprising means for holding the mount with a lead wire thereof extending vertically at a work station, means for supplying a pool of getter paste at a position adjacent said work station, an arm having an axially rotatable end portion and movable through a horizontal plane between the getter supplying means and the work station, a finger having a notched end extending laterally from the rotatable end of the arm, means for rotating the rotatable end portion of the arm during the movement thereof to cause the notched end of the finger to extend downward from said arm and be immersed in the getter pool at one terminus of the motion thereof and to cause said notched end to extend approximately horizontally, and take a position about a portion of the said lead wire at the other terminus of said motion, and means for moving the arm vertically at the work station to cause the notched end of the finger to wipe along a portion of the lead wire.

4. Apparatus for applying a getter paste to a lead wire of a mount comprising means for holding the mount at a work station, a main supply reservoir for the getter paste at a position adjacent the work station, an arm having an axially rotatable end portion and movable between positions over the getter reservoir and the work station, a finger having a notched end extending laterally from the rotatable end portion of the arm, a spoon for lifting a quantity of the getter paste to a position above the reservoir, and means for rotating the rotatable end portion of the arm during the movement thereof to cause the notched end of the finger to be immersed in the getter paste in said spoon at one terminus of the motion and to cause the notched end to take a position about a portion of said lead wire at the other terminus of said motion.

5. Apparatus for applying a getter paste to spaced lead wires of a mount comprising means for holding the mount with the leads at a definite position at a work station, means for supplying a pool of getter paste at a position adjacent said work station, an arm having an axially rotatable end portion movable between the getter supply means and the work station, a pair of fingers having notched ends and extending laterally from the rotatable end portion of the arm in spaced relation corresponding to the spacing of the said lead wires, and means for rotating the rotatable end portion of the arm during the movement thereof to cause the notched ends of the fingers to be immersed in the getter pool at one terminus of the motion and to cause the notched ends to take positions about respective lead wires at the other terminus of said motion.
6. Apparatus for applying a getter paste to spaced lead wires of a mount comprising means for holding the mount with the lead wires at a definite position at a work station, means for supplying a pool of getter paste at a position adjacent said work station, an arm having an axially rotatable end portion movable between the getter supply means and the work station, a pair of fingers having notched ends and extending substantially in a radial direction from the end portion of said arm and spaced apart both longitudinally and circumferentially along said arm, and means for rotating the said rotatable end portion of the arm during the movement thereof to cause the notched ends of the fingers to be immersed in the getter pool at one terminus of the motion and to cause the notched ends to take positions about respective lead wires of the mount at the other terminus of said motion.
7. Apparatus for applying a getter paste to spaced lead wires of a mount comprising means for holding the mount with the lead wires thereof extending vertically at a work station, a main supply reservoir for the getter paste at a position adjacent the work station, an arm having an axially rotatable end portion and movable through a horizontal plane between positions over the getter reservoir and the work station, a pair of fingers having notched ends and extending substantially in a radial direction from the end portion of said arm and spaced apart both longitudinally and circumferentially along said end portion of the arm, a spoon for lifting a quantity of the getter paste to a position above the reservoir, and means for rotating the rotatable end portion of the arm during the movement thereof to cause the notched ends of the fingers to extend essentially downward from said arm and be immersed in the getter paste from the quantity in the spoon at one terminus of the motion and to cause the notched ends to extend approximately horizontally and take vertically spaced positions about respective lead wires of the mount at the other terminus of said motion.
